UNITED STATES PATENT OFFICE.

JAMES H. CODDING, OF NORTH DIGHTON, MASSACHUSETTS.

RANGE.

SPECIFICATION forming part of Letters Patent No. 256,885, dated April 25, 1882.

Application filed March 10, 1882. (No model.)

To all whom it may concern:

Be it known that I, JAMES H. CODDING, of North Dighton, in the county of Bristol and State of Massachusetts, have invented certain new and useful Improvements in Ranges; and I do hereby declare the following to be a full, clear, and exact description of the same, reference being had to the accompanying drawings, forming a part of this specification, in ⁵ which—

Figure 1 is a perspective view of my invention. Fig. 2 is a sectional view taken on the line *xx*, Fig. 1. Fig. 3 is a similar view taken on the line *yy*, Fig. 1.

¹⁵ Similar letters of reference in the several figures denote the same parts.

My invention consists in combining with the "cabinet-base," so called, of a range, an independent ash-box secured within said base ²⁰ and accessible through the front of the same, and a sifting-grate supported in a frame above the ash-box, the whole constructed and arranged substantially as described hereinafter.

Referring to the accompanying drawings, ²⁵ A represents the base part of a range, known to the trade as a "cabinet-base." Upon the top of this base is fitted and rests a metal frame, B, the part B' of which serves as the bottom

of the range proper. Mounted in this frame B, at one side thereof, is a longitudinally-moving sifting-grate, B². Beneath said sifting-grate, and secured by any suitable means within the cabinet-base, is the ash-box C, the same being accessible through a front opening in the base, closed by a door, D, as shown. Contained within the ash-box is an ash-pan, E, as shown. The frame or plate B, carrying the sifting-grate, is detachable from the base, and said frame and the base are thus arranged so that either of them can be shipped or transported separate from the other, while they can be readily put together by any unskilled person.

Having thus described my invention, I claim as new—

The combination, substantially as described, of the cabinet-base of a range, the detachable plate or frame supported thereby and carrying the sifting-grate, and the independent ash-box attached to the base within the same and ⁴⁵ beneath the sifting-grate.

JAMES H. CODDING.
